DESIGN FOR A BOTTLE OR SIMILAR ARTICLE

Richard Sussman, New York, N. Y.

Application May 15, 1941, Serial No. 100,951

Term of patent 7 years

To all whom it may concern:

Be it known that I, Richard Sussman, a subject of the Kingdom of Egypt and a resident of the Borough of Manhattan, in the county, city, and State of New York, have invented a new, original, and ornamental Design for a Bottle or Similar Article, of which the following is a specification, reference being had to the accompanying drawing, forming a part thereof.

Fig. 1 is a top plan view of a bottle showing my new design.

Fig. 2 is a front elevational view thereof.

Fig. 3 is a side elevational view thereof.

I claim:

The ornamental design for a bottle or similar article, substantially as shown.

RICHARD SUSSMAN.
